UNITED STATES PATENT OFFICE.

EDGAR M. HAWKINS, OF ROCHESTER, NEW YORK, ASSIGNOR TO M. D. KNOWLTON COMPANY, OF ROCHESTER, NEW YORK, A CORPORATION OF NEW YORK.

BOX-COVERING MACHINE.

1,302,546.

Specification of Letters Patent. Patented May 6, 1919.

Application filed July 19, 1917. Serial No. 181,510.

To all whom it may concern:

Be it known that I, EDGAR M. HAWKINS, a citizen of the United States, and resident of Rochester, in the county of Monroe and State of New York, have invented certain new and useful Improvements in Box-Covering Machines, of which the following is a specification.

This invention relates to that class of machines which are adapted to apply a covering of paper to the tops and bottoms of paper or straw-board boxes or the like, and is directed particularly to the mechanism for controlling the movable knife which operates to sever the paper from the supply strip.

An object of the invention resides in the provision of electrically actuated means for permitting the movable knife to operate and which is subject to the direct control of the operator.

A further object of the invention resides in the provision of a mechanism wherein the movable knife is automatically rendered inoperative and returned to its initial position.

A further object of the invention resides in incorporating the controlling mechanism in the work support whereby the operator may bring about the actuation of the movable knife with the greatest facility and a minimum consumption of time.

A still further object of the invention resides in so constructing the device that it may be applied not only to newly constructed machines, but also to various machines which are at present on the market.

In the drawings:

Figure 1 is a side elevation of a portion of a topping machine with the invention incorporated therein; and

Fig. 2 is an elevational view partly broken away, looking at right angles to Fig. 1.

In the drawings, a portion of the frame 1 of a topping machine is illustrated, which carries at its upper end the usual paper strip guide roller 2. Mounted on the forward side of the frame 1 is a work support which comprises a base 3 and a table 4, which latter is hinged at 5 to a block 6 carried by the upper side of the base 3. The table 4 is normally urged away from the base 3 by coiled springs 7 which are disposed between the block 6 and the table. The upward movement of this table 4 is, however, limited by a stop 8, and the space between the table and the base

is inclosed by an apron 9 carried by the table and movable therewith. This work support is provided with the usual vertical standard 10 and adjusting devices 11, so that it may be moved either vertically upward or downward and horizontally in transverse and lateral directions, in the manner which is usual in machines of this general type.

Mounted on the upper end of the frame 1 and disposed between the guide roller 2 and the work table 4 is a stationary knife 12 over which the strip of paper passes and with which a movable knife 13, carried by a shaft 14, is arranged to coöperate. The movement of the knife 13 toward the stationary knife 12, about the axis of the shaft 14 as a pivot, is cushioned by a spring 15 in a usual and obvious manner, which spring is put under compression by the movement of the knife and, therefore, subsequently assists in returning the knife to its inoperative position.

In order that the operator may bring about the movement of the knife 13 to sever the strip of paper at the desired times and without removing his hands from the work table, the following mechanism is provided. A lever 16 is pivoted at 17 to the frame of the topping machine and is normally drawn upwardly by a coiled spring 18 which is secured to the lever between the fulcrum of the same and the power point and to the frame 1 of the topping machine at 19. Extending from and rigid with the shaft 14 is an arm 20, to which is attached a connecting rod 21 having a turn buckle 22 therein, by means of which its length may be varied. The other end of this connecting rod is provided with an elongated slot 23 through which a pin 24 on the lever 16, extends. This lever 16 is normally held by the spring 18, so that the pin 24 is located in the upper end of the slot 23, for the purpose of supporting the knife through the rod. A link 25 is pivoted at 26 to the power end of the lever, and at 27 to the core 28 of a solenoid magnet 29. This magnet is supported on the frame 1 of the machine by suitable brackets 30.

Thus it will be seen that the energizing of the magnet 29 will cause the movement of the core 28, and, consequently, the downward movement of the lever 16 about its pivot, and that when the magnet is deenergized, the spring 18 will cause the upward movement of the lever 16 about its pivot until such movement is arrested by a stop 110

31, which is located on the frame and is arranged to engage the lever. The solenoid magnet 29 is interpolated in a circuit which includes supply and return wires arranged 5 in a cable 32, which wires extend to a suitable source of electrical energy (not shown), and one of which, 33, extends to a binding post 34 carried by the base 3, and the other of which, 35, extends to a binding post 36, 10 which is carried by the work table 4. These binding posts are insulated from the respective parts by which they are carried by suitable insulating plates 37, to which plates contacts 38 are attached by screws 39, or 15 other equivalent means. The heads of these screws are insulated from the adjacent portions of the base 3 and table 4 by suitable insulating material 40. The contacts 38 are connected to the binding posts 34 and 36 by 20 suitable conductors 41. The springs 7 normally maintain the work table 4 in a raised position, as aforesaid, and the contacts 38 out of engagement with each other.

When it is desired to sever the paper 25 from the supply strip, in the covering operation, it is only necessary for the operator to depress the work table 4, either by means of applying force to the box which is being operated upon or directly to the table. This 30 movement of the work table 4 will cause the engagement of the contacts 38 and the completion of the circuit through the solenoid magnet 29. This magnet, being energized, will draw the core 28 downwardly, and consequently move the lever 16, so that the pin will pass to the lower end of the slot 23 in the rod 21. This will permit the movable knife 13 to drop under the action of gravity and thus sever the paper. It is, of course, 35 to be here understood that the force exerted by the magnet is appreciably greater than that exerted by the spring 18, and, consequently, the lever 16 will move downwardly in spite of the spring when the magnet is energized. Moreover, the spring 18 is of 40 such strength that when the magnet 29 is de-energized, it will cause the upward movement of the lever 16, together with the core 28, and the consequent resetting of the movable knife 13.

Under ordinary conditions, the knife 13 will fall as soon as the pin 24 is moved to the lower end of the slot 23, but it may occur that the bearings for the knife 13 are 45 too tight, or the knife otherwise becomes stuck and hard to move, in which event, the knife will not fall under the action of gravity. Therefore, the core 28 is allowed movement somewhat in excess of the length 50 of the slot 23, so that, should the pin 24 move to the extreme lower end of the slot 23 before the knife 13 has moved, the movement of the core 28 will, through the engagement of the pin 24 with the lower end 55 of the slot, produce a downward pull on the

rod 21 and start the knife 13. The extent of the movement of the core 28 is, however, limited so that at no time, other than that which has just been referred to, will the movable knife be drawn downwardly positively. Thus in the event of an operator accidentally getting his or her hand between the knives, no injury will result, as the knife will fall by gravity and its weight or extent of movement will not be sufficient to 75 cause injury.

It will thus be seen that when the work table is depressed, the magnet will be energized, and, consequently, the movable knife 13 be released, so that it may move downward and operate under the action of gravity, and further, that upon the breaking of the energizing circuit for the magnet, the knife, together with the remaining parts, will be automatically returned to their initial positions ready for another operation.

What I claim is:—

1. In a box covering machine, the combination with a movable knife, of a movable work table, and electrically operated means controlled by the movement of the table for controlling the movement of the knife.

2. In a box covering machine, the combination with a movable knife, of a movable work table, and magnetic means controlled by the movement of the table for controlling the movement of the knife.

3. In a box covering machine, the combination with a gravity actuated knife, of means for raising the same and maintaining it in its raised position, and electrically controlled means for rendering the first-mentioned means inoperative.

4. In a box covering machine, the combination with a movable knife, of means for preventing the movement of the same, and electrically controlled means for rendering the first-mentioned means inoperative and for initially imparting movement to the knife.

5. In a box covering machine, the combination with a movable knife, of means for preventing the movement of the same, and electrically controlled means for rendering the first-mentioned means inoperative and for initially imparting movement to the knife, but incapable of continuously imparting movement to the knife.

6. In a box covering machine, the combination with a movable knife, of a movable work table, a solenoid magnet interpolated in an open circuit for controlling the movement of the knife, and means rendered operative, upon a movement of the table, to close the circuit through the magnet whereby the latter will be energized and the knife permitted to fall.

7. In a box covering machine, the combination with a gravity actuated knife, of

5 a support, a movable work table mounted thereon, means for normally maintaining the knife in its raised position, and means for rendering said last-mentioned means inoperative which includes a solenoid magnet which is interpolated in an open circuit, the terminals of which are carried by the support and table and are moved into contact with each other upon a movement of the

10 table.

15 8. In a box covering machine, the combination with a gravity actuated knife, of a support, a movable work table mounted thereon, means for normally maintaining the knife in its raised position, means for rendering said last-mentioned means inoperative which includes a solenoid magnet which is interpolated in an open circuit the terminals of which are carried by the support and table and are moved into contact with each other upon a movement of the table, and means for automatically returning the table to its initial position and breaking the circuit.

20 25 9. In a box covering machine, the combination with a gravity actuated knife, of means for automatically raising the same and for normally maintaining it in its

raised position, and electrically operated means for rendering said first-mentioned means inoperative.

10. In a box covering machine, the combination with a gravity actuated knife, of means for raising the same and normally maintaining it in its raised position, magnetic means for rendering said first-mentioned means inoperative, and a movable work table, the movements of which control the energization of the magnet.

11. In a box covering machine, the combination with a gravity actuated knife, of means for automatically raising the same and normally maintaining it in its raised position, magnetic means for rendering said first-mentioned means inoperative, and a movable work table, the movements of which control the energization of the magnet.

Signed at Rochester, in the county of Monroe, and State of New York, this 14 day of July, A. D. 1917.
